Patented Oct. 24, 1916.

UNITED STATES PATENT OFFICE.

ALEXANDER C. RINDSKOPF, OF KANSAS CITY, MISSOURI, ASSIGNOR TO KEYSTONE
VARNISH COMPANY, OF BROOKLYN, NEW YORK.

DISPLAY COLOR-CARD.

1,202,586.

Specification of Letters Patent.

Patented Oct. 24, 1916.

Application filed October 15, 1914. Serial No. 866,788.

To all whom it may concern:

Be it known that I, ALEXANDER C. RINDSKOPF, a citizen of the United States, residing at Kansas City, Jackson county, Missouri, have invented a new and useful Display Color-Card, of which the following is a specification.

My invention relates to improvements in display color cards, in which the effect of 10 various tints or patterns intended for use on the walls or ceilings of rooms can be easily and quickly shown in combination with other tints or patterns, together with a representation of a room with furniture, 15 and the trade number or name of the said tint or pattern. These objects I attain by the device illustrated in the accompanying drawings, in which—

Figure 1 is a plan view of my invention. 20 Fig. 2 is a sectional view on line 2—2 of Fig. 1. Fig. 3 is a sectional view on line 3—3 of Fig. 1. Fig. 4 is a plan view of the rotating disk carrying the tints or patterns. Fig. 5 is a detailed view showing a means 25 of stopping and holding in correct position the tint or pattern to be displayed.

Similar reference numerals refer to similar parts throughout the several views.

In the embodiment of the invention here- 30 in shown, an upper member 10 contains a representation of a room 11 and is provided with a color display slot 12 arranged as a cut-out of a portion of the wall of the room represented. This upper member is also 35 provided with a smaller slot 16 which is preferably in radial relation to the larger slot 12. This smaller slot is herein designated as a trade character slot.

A rotary under member 14 in the form of 40 a disk is pivoted by means of a headed pivot pin 15 or otherwise beneath the upper member 10. This rotary under member is provided with an outer circular series of color display panels 13 containing a variety 45 of colors or tints to be displayed. This rotary under member is also provided with an inner circular series of the numbers or names or other trade designations used to indicate the particular tint or pattern. 50 These trade designations are in fixed relation to the panels so that when the rotary disk is turned to cause any given panel to register with the color display slot of the upper member, the particular trade designation belonging to that panel will be simulta-

neously exhibited through the smaller slot 16 of said upper member 10. The slot 12 of the upper member is preferably seg- 60 mental in form and the several color or tint panels of the lower member are also pref- erably of segmental form and correspond in size to said slot. The segmental shape not only gives a larger display surface but corresponds in perspective with the represen- 65 tation of the room.

In the spaces 18 on the upper member 10, 65 reading or advertising matter may be printed.

To provide for the easy manipulation of the rotating disk 14 one side of the upper 70 member 10 is cut away as at 19, so that the edge of the disk may be readily grasped.

In the space 22, if desired, a contrasting 75 ceiling tint or pattern can be displayed so that the general effect of a furnished room with finished wall and ceiling is obtained.

It is obvious that the number of tints or 80 patterns 13 with their corresponding indicating names or numbers 17, may be increased or decreased, by enlarging or diminishing the size of the disk 14.

The means shown in Fig. 5 for positioning the disk 14 so that the tint or pattern 13 will be located exactly in the opening 12, 85 consists of a spring catch 20 attached to the upper member 10 at 19 so that it is held against the edge of the disk 14, in which notches 21 are cut at intervals spaced so that when the spring catch engages with one of the said notches, the disk is held 90 against rotation and the pattern or tint space 13 completely fills the opening 12.

The preferred embodiment of my invention shown herein has a number of advantages in that a tint or pattern can be shown 95 as it will appear on a wall surface in conjunction with the furniture of a room and in contrast with a tint or pattern on a ceiling and in addition the indicating symbol of the particular tint being displayed, is 100 plainly visible.

I do not desire to limit myself strictly to the preferred form shown and described herein as this is but one of many modifications within the spirit of my invention.

I claim—

1. A color display card comprising an upper member containing a representation of a room and provided with a color display slot arranged as a cut-out of a portion 110

of the wall of the room represented, and a rotary under member pivoted beneath said upper member and provided with a circular series of color display panels severally adapted to register with said color display slot and containing a variety of colors or tints.

2. A color display card comprising an upper member containing a representation

19 of a room and provided with a segmental color display slot arranged as a cut-out of a portion of the wall of the room represented, and a rotary under member pivoted beneath said upper member and provided with

15 a circular series of segmental color display panels severally adapted to register with said color display slot and containing a variety of colors or tints.

3. A color display device comprising an
20 upper member containing a representation of a room and provided with a color display

slot arranged as a cut-out of a portion of the wall of the room represented and provided with a trade character slot, and a rotary under member pivoted beneath said 25 upper member and provided with an outer circular series of color display panels containing a variety of colors or tints and with an inner circular series of trade designations of the colors or tints of the respective panels in fixed relation to said panels, the respective panels and corresponding trade designations being adapted to register simultaneously with said slots of the upper member.

35 In witness whereof I have hereunto set my hand this 13th day of July, 1914.

ALEXANDER C. RINDSKOPF.
